UNITED STATES PATENT OFFICE

146,719

DESIGN FOR A CLOTHESPIN

William Kaufman, Winfield Park, N. J.

Application July 12, 1946, Serial No. 131,517

Term of patent 7 years

(Cl. D17—6)

To all whom it may concern:

Be it known that I, William Kaufman, a citizen of the United States, residing in Winfield Park, county of Union, and State of New Jersey, have invented a new, original, and ornamental Design for a Clothespin, of which the following is a specification, reference being had to the accompanying drawing, forming part thereof.

In the drawing:

Figure 1 is a perspective view of the clothespin, showing my new design;

Figure 2 is a front view, the rear view presenting substantially the same appearance; and

Figure 3 is a side elevational view.

I claim:

The ornamental design for a clothespin, as shown and described.

WILLIAM KAUFMAN.
